UNITED STATES PATENT OFFICE.

EDWARD D. GREEN AND EMILY M. SCOTT, OF CHICAGO, ILLINOIS.

COMB.

1,282,070.

Specification of Letters Patent. Patented Oct. 22, 1918.

Application filed June 26, 1918. Serial No. 242,012.

To all whom it may concern:

Be it known that we, EDWARD D. GREEN and EMILY M. SCOTT, citizens of the United States, residing at Chicago, county of Cook, 5 and State of Illinois, have invented a new and useful Improvement in Combs, of which the following is a specification.

The invention relates to combs and particularly of the kind used for hair or wool.

10 It is an object of the invention to provide a comb which is adapted to straighten out the curls in wool or hair.

A further object embraces the provision of a comb with a back adapted to be heated 15 and to impart the heat to the teeth of the comb.

A further object includes the provision of means for internally heating the back portion of the same.

20 It is also an object of the invention to provide a handle to which the improved comb is detachably secured and may be exchanged for a comb of ordinary or modified construction.

25 To the accomplishment of the objects stated and others that will become apparent as the description proceeds, the invention comprises the means hereinafter set forth and specifically pointed out in the appended 30 claim.

Figure 1 is a side view of a comb, constructed in accordance with the invention.

Fig. 2 is a sectional view of the comb equipped with internal electrical heating 35 means, and

Fig. 3 is a perspective view of a comb adapted to be heated by an external source of heat.

Referring to the drawing, 1 designates a 40 handle of ordinary construction provided with an axial bore for the passage of wires 2, 3, which may be connected to a lamp socket in the well known manner. To the handle 1 a shank or stem 4 is secured either 45 by threaded engagement therewith or by permanent attachment thereto, and the forward portion of said shank is enlarged to constitute a socket member 5, and said member is 50 interiorly threaded at 5' and formed with a cylindrical seat 5", the socket member being adapted for the reception of a reduced threaded extension 6 of the comb. The latter, as shown in Figs. 1 and 2 comprises a 55 hollow back portion 7 and a plurality of spaced teeth 8, which, as shown, may be

formed integral with the back or if preferred may be constructed separately and properly secured to the back.

Incased in the back 7 is an electrical heating element 9, having a plug member 9', which 60 fits into the socket member 5, on the seat 5", serving when the reduced threaded extension of the comb is screwed into the threaded portion 5', of the socket to hold the heating elements centrally of the bore in 65 the back of the comb and spaced from the side walls thereof. When the parts are screwed together the end of the reduced extension 6, will engage a portion of the upper 70 face of the plug 9', and, in assembled relation of the comb parts the plug member 9' is placed in contact with the wires 2 and 3 to connect the heater with the source of electric energy.

From the foregoing it is obvious that 75 when the circuit through the wires 2, 3 is closed, heat will be generated in the interior of the back member 7 which heat is transmitted by conduction to the teeth 8 and given off to the hair or wool so that in the 80 combing operation curls are straightened.

In Fig. 3 a modified comb is shown comprising a solid back portion 10 formed integral with teeth 11. The back 8 terminates in a reduced threaded extension 12, adapted 85 to be screwed into the socket member 5. When the comb, shown in Fig. 3 is used, electric heating is dispensed with and it is intended to heat the back of the comb by an 90 external source of heat, such as a gas flame. 90

The improved comb is intended to be used for straightening the curls of the hair especially of colored people and also to comb wool. Various modifications and changes 95 may be made without departing from the spirit of the invention and it is therefore my intention of including all alterations constituting departures within the scope of the invention as defined in the appended claim.

We claim:

An electrically heated comb, comprising a 100 comb section having a hollow back, a handle for said comb section, formed with a shank, said shank having an interiorly threaded socket and a seat at one end, said comb section being formed with a reduced threaded 105 extension adapted for threaded engagement in said socket, an electric heating element disposed in the hollow back portion of the comb section, and a plug member on said 110

heating element adapted to be mounted on the socket seat, the reduced extension of said comb section adapted for engagement with said plug for holding said heating element 5 in said comb section and spaced from the walls of the hollow back of said comb section.

Copies of this patent may be obtained for five cents each, by addressing the "Commissioner of Patents. Washington, D. C."

In testimony whereof we affix our signatures in the presence of two witnesses.

EDWARD D. GREEN.
EMILY M. SCOTT.
